COMPOUND INTERNAL-COMBUSTION
TURBINE PLANTFritz Albert Max Heppner, Leamington Spa, Eng-
land, assignor to Armstrong Siddeley Motors
Limited, Coventry, EnglandApplication August 31, 1943, Serial No. 500,694
In Great Britain September 3, 1942

3 Claims. (Cl. 230—123)

1

Of internal-combustion turbine plants—whether for jet-propulsion purposes or for driving a ship's propeller, an electrical generator or the like—the compound type (i. e., one having separate compound sections each including a rotating turbine section driving a compressor section) is theoretically ideal; but it is extremely complicated mechanically, leading *inter alia* to difficulty in the lubrication and cooling of the bearings, and sealing problems occur on many stages particularly at large diameters.

My main object is to provide an improved compound internal-combustion turbine plant with which these difficulties will be reduced.

For an understanding of this and other objects and advantages of the invention attention should be directed to the following description in which reference is made to the accompanying sheets of diagrammatic drawings, wherein:

Figure 1 is a temperature/entropy diagram for a known form of compound turbine plant, and Figure 2 a temperature/entropy diagram for a compound plant according to the invention; whilst

Figure 3 is an axial section through half a compound plant according to the invention.

It is believed that, from a comparison of Figures 1 and 2, those skilled in the art will readily appreciate the thermodynamic advantages of the present invention, Figure 2 showing how useful work is taken out between all the adjacent turbine sections.

According to the main feature of the invention, work is taken out between adjacent compound sections so that the pressure at the end of a compressor section and that at the beginning of the associated turbine section are substantially equal. Preferably the pressure at the end of a compressor section is not less than the pressure at the beginning of the associated turbine section, whereby to reduce any tendency for leakage to take place from the turbine section to the associated compressor section.

The invention further consists in a compound internal-combustion turbine plant as aforesaid having axially-disposed compressor sections arranged radially within the associated turbine sections which are also axially disposed. The fluid flow is preferably in one direction through the compressor sections and in the opposite direction through the turbine sections. Such a plant, particularly one for jet-propulsion purposes, may be of the contra-rotating type, comprising a rotary drum or shell common to all the turbine sections, i. e., carrying internally-extending blades for all

the turbine sections, rotary compressor members in each section carrying externally-extending compressor blades and also externally-extending turbine blades of the associated turbine sections, and stationary internally-extending compressor blades carried by shrouds between the compressor and turbine sections.

In the specific construction of Figure 3, wherein these features are shown, the compound turbine plant is for jet-propulsion purposes, and it comprises a stationary shaft 10 upon which are mounted, as through ball bearings 11, 11, compressor members 12, 13, 14 and 15, 12 representing the member of the first compressor section and 15 that for the last section. Each compressor member carries external rows of blades 16, 16, and at least one of these rows, 16a, of blades in each section extends radially outwardly beyond stationary shrouds 17, which are fast with the shaft 10, to carry a ring of turbine blades 18 by which the associated compressor member can be driven, this constituting a compound section. There are many more turbine blades 18 in a row than compressor blades in a row. Journalled at 20, 20 is a rotary drum or shell 21 which is common to all the turbine sections, the shell carrying sets of blades 22, 23, 24 and 25 with which coat the different turbine blades 18. The shrouds 17, it will be observed, segregate the turbine sections from the compressor sections.

In the present instance, there is associated with the plant a jet-augmenter comprising external blades 27 on the turbine shell 21 and internal blades 28 on a stationary casing 29 having outside it a streamlined cowling 30 tapering inwardly at its rear to define the outer boundary of the jet 31. Some of the air from the augmenter is delivered through the opening 33 directly into the jet, and the rest of it is delivered by stationary, finger-shaped pipes 34, which are curved through 180°, to the first compressor section, as disclosed in the specification of my co-pending patent application Serial No. 500,698 filed August 31, 1943. The outlet from the last turbine section is between the pipes 34 into the jet 31.

To take the axial thrust of the shell I provide labyrinth 36 and 36a, preferably multi-stage labyrinth of known form, bounding the annular space 37 to which air is fed along passages 37a from the point of maximum pressure. Return passages 38 lead from the labyrinth 36 to different turbine sections, and these serve for cooling the turbine shell 21.

At 40 is indicated diagrammatically a member 55 in the combustion chamber, and at 41 a fuel

jet. The member 40 is stationary, and a ring of blades 42 coacts with the inlet opening of the member, the said blades being supported from the compressor member 15 of the last stage.

For driving auxiliaries I may provide a spur-gear 43 on the last compressor member 15 to gear with a spur-gear on a layshaft 44.

In this way I provide a contra-flow, contra-rotating, jet-augmenter type of internal-combustion turbine plant with compound characteristics. No special regulating means are necessary and there is no leakage from the turbine sections to the associated compressor sections, assuming the design to be such that slightly greater pressures are obtained, respectively, in the compressor sections. The combustion chamber is stationary and the plant can be easily started up.

The compressor is shown as being in four sections each giving a compression ratio of about 2, in which case stalling in the compressor sections will not take place whilst a very high overall compression (about 16 to 1) can be obtained. Furthermore, the Mach number in the turbine and compressor is low, the mechanical stresses are low and the overall weight is very low. Optimum efficiency is provided in all conditions and perfect energy balance, whilst the plant is short and compact and there is no danger of its bursting. The axial thrust is taken by the air supplied to the annular space 37, the leakage air being used as a coolant.

Whilst I show at 40, 41 a diagrammatic combustion chamber primary air for which is delivered by the blades 42, a preferred form of combustion chamber is as disclosed in the specification of my co-pending application Serial No. 500,696 filed August 31, 1943.

What I claim as my invention and desire to secure by Letters Patent of the United States is:

1. In a compound internal-combustion plant of the axial flow type separate compound sections each including a rotating turbine section driving a compressor section, the highest and lowest pressure turbine sections driving the highest and lowest pressure compressor sections, respectively, said sections being so arranged that the flow through the turbine sections is in the opposite axial direction to that through the compressor sections, contra-rotating turbine

members interposed between said turbine sections, and means drivably connected to said contra-rotating turbine members for doing useful work, said contra-rotating turbine members being so designed that the pressure at the end of a compressor section is slightly greater than the pressure at the beginning of the associated turbine section, whereby leakage from the turbine sections to the associated compressor sections is substantially prevented.

5 2. A compound internal-combustion turbine plant of the axial flow type for jet-propulsion purposes, comprising a plurality of axially-arranged, rotary compressor members, a plurality of axially-arranged turbine members respectively connected to and driving said compressor members, a jet-augmenter having a rotary bladed member and a cooperating stationary bladed member coaxial with and surrounding said compressor and turbine members, and contra-rotating turbine members interposed between said first named turbine members and drivably connected to the rotary bladed member of the jet-augmenter, said compressor and turbine members arranged so that the flow is in opposite axial directions therethrough.

15 3. A turbine plant, according to claim 2, having said compressor members arranged radially within the turbine members to which they are 20 respectively connected.

30 FRITZ ALBERT MAX HEPPNER.
